UNITED STATES PATENT OFFICE.

ARNOLD MICHOU, OF YVERDON, SWITZERLAND, ASSIGNOR TO CIBLES AUTOMATIQUES
MICHOU SOCIÉTÉ ANONYME, OF NEUCHATEL, SWITZERLAND.

DEVICE FOR RESILIENTLY SUPPORTING TARGET DISKS AND THE LIKE.

Application filed March 31, 1923. Serial No. 628,996.

To all whom it may concern:

Be it known that I, ARNOLD MICHOU, a citizen of Switzerland, residing at Yverdon, Canton of Vaud, in the Confederation of Switzerland, have invented certain new and useful Improvements in Devices for Resiliently Supporting Target Disks and the like, of which the following is a specification.

10 In the case of targets with an automatic indicator device, in which the bullet on striking the target closes an electric circuit which acts on the indicator device and operates the same, the want has been naturally 15 felt of a certain elasticity of the target or of its parts in the rearward direction. Targets are already known in which the single parts or sections are mounted on bolts passing through rubber sleeves. As however 20 provision has also been already made for preventing the bolts from yielding in the lateral directions by means of a metal guide which tightly surrounded them about the centre of their length, the target parts could 25 yield only in the rearward direction.

Practical experience has however shown that targets mounted so as to yield only in the longitudinal direction of the bolts, were a constant source of costly repairs. The 30 bolts, rivet heads and the like, by means of which the target parts are held, break very soon owing to their being mounted only in a partially elastic manner.

This invention relates to a method of 35 silently mounting targets with automatic indicator devices and like devices, which is characterized by the target disk or disk sections or the like arranged at a distance from their indirect supporting organs, resting on 40 stay bolts which are mounted so as to be elastic in the axial and in the radial directions, so that provision is made for a certain amount of play in every direction.

Two constructions according to the invention, as applied to target disks, are illustrated by way of example in the accompanying drawing.

Fig. 1 is a cross-section through the target supporting device, whilst

50 Fig. 2 shows it in front elevation, partly in section and

Fig. 3 in rear elevation.

Figs. 4 and 5 are respectively a front ele-

vation and a side elevation of the target disk provided with the elastic supporting device. 55

Fig. 6 shows a second construction in cross-section, and

Figs. 7 and 8 are respectively a front elevation and a side elevation of the target disk provided with the supporting device of this 60 second construction.

In the drawings, 1 is a supporting part, 2 the disk, 2^a—2^b single sections of the disk 2, 3 the stay bolt, 4 the rubber bearing of the first construction, 5 a screw threaded sleeve 65 nut, 6 a recess in the supporting part 1, 7 a metal ring or washer, 8 the rubber bearing according to the second construction, 9 a metal cap, 10 a second metal washer.

In the first construction (Figs. 1 to 5), the shank of the bolt 3 passes through a correspondingly dimensioned recess of the disk 2, and the head of the bolt 3 is brought to engage firmly with the disk 2, by tightening the sleeve nut 5. The stay bolt 3 is then 70 passed through a recess 6 of the supporting plate 1. A protector metal ring or washer 7, the inside diameter of which corresponds to the outside diameter of the part of the screw threaded sleeve 5, which faces it, so 75 that it can be put over the same, and the outside diameter of which is greater than that of the recess 6 in the supporting part 1 is thereupon placed against the latter, whereupon 80 the rubber bearing 4 which tightly encloses 85 the shank of the bolt 3 on a portion of its length, is pushed over the same. The metal cap 9 is then placed over the rubber bearing 4, the internal dimensions of said cap exactly corresponding to the dimensions of the 90 said bearing, and secured to the supporting part 1 by means of bolts which are prevented in the usual manner from getting loose.

A metal ring 10 is then placed over the 95 shank of the bolt 3, and the whole firing device is secured by means of a split pin passed through the shank.

This construction is preferably used for 100 heavy target disks.

In the second construction such as it is shown in Figs. 6-8, the single cylindrical rubber bearing 4 for each stay bolt 3, is replaced by strips of rubber 8 in which are mounted a number of stay bolts 3 arranged in one and the same straight line. The rub-

ber strips are secured to the supporting part by means of bolts which are provided in the intervals between each two consecutive stay bolts 3, as shown in Fig. 6.

5 This construction is chiefly intended for lighter target disks.

In both constructions the metal rings 7 protect the rubber bearings from penetration of projectile particles or from any other 10 mechanical injury.

This method of supporting the target disk allows the latter to yield in the rearward direction as well as in any lateral direction; the target is elastic in the axial as 15 well as in the radial directions, owing to which the object of the invention, namely to protect the parts (stay bolts, rivets, etc.) by means of which the target disk or its sections are held on, or in, the supporting 20 part 1, from injury and breakage, is attained in a very simple manner.

It goes without saying that the axial and radial elasticity of the supporting part could also be ensured in some other way than by 25 mounting the stay bolts in bearings of rubber or other resilient material, for instance by guiding and mounting the stay bolts 3 or their substitutes by means of springs on all sides. These other constructions also 30 come within the present patent protection.

Having now particularly described and ascertained the nature of my said invention and in what manner the same is to be performed, I declare that what I claim is:—

35 1. A device for resiliently supporting target disks and the like comprising a supporting member, a disk or disk sections, stay bolts on which said disk or disk sections are secured, the said stay bolts passing freely through said supporting member, and means associated with the supporting member for yieldingly engaging the stay bolts to normally maintain the same and the disk or disks in position and when the 40

disk or disks are struck to permit the stay 45 bolts to move radially as well as axially.

2. A device as in claim 1, the said stay bolts being held in a rubber bearing adapted to tightly enclose the shank of the stay bolts on a portion of their length. 50

3. A device as in claim 1, wherein an elastic bearing of the stay bolts is arranged in a metal cap which is detachably connected to the supporting member of the target disk or the like. 55

4. A device as in claim 1, wherein the stay bolts are arranged in one and the same straight line and are mounted in a strip of elastic or resilient material, which in the intervals between each two adjacent stay 60 bolts is secured in a suitable manner to the supporting member of the target disk or the like.

5. A device as in claim 1, wherein a screw-threaded sleeve is provided for bringing the 65 disk or disk sections mounted on the shank of the stay bolts into a thorough engagement with the bolt head, the member supporting the target disk being provided with recesses, the diameter of which is greater than the diameter of the said screw-threaded sleeve, and wherein further a metal ring on the rear end of the screw-threaded sleeve and extending across the recess in the supporting member and another metal ring arranged between an elastic bearing of the 70 stay bolts and a rear clock for the former, is provided for the purpose of protecting the said elastic mounting from any mechanical damage by the penetration of projectile 75 particles and other foreign substances. 80

In testimony whereof I have affixed my signature in presence of two witnesses.

ARNOLD MICHOUUD.
